UNITED STATES PATENT OFFICE.

MATHIAS ZEINER, OF MCKEESPORT, PENNSYLVANIA.

DISPLAY-RACK.

No. 838,294.

Specification of Letters Patent.

Patented Dec. 11, 1906.

Application filed April 2, 1906. Serial No. 309,377.

To all whom it may concern:

Be it known that I, MATHIAS ZEINER, a subject of the Emperor of Austria-Hungary, residing at 2317 Fifth avenue, McKeesport, 5 in the county of Allegheny and State of Pennsylvania, have invented certain new and useful Improvements in Display-Racks, of which the following is a specification, reference being had therein to the accompanying drawings.

This invention relates to certain new and useful improvements in display-racks; and the invention has for its primary object to provide a novel form of revoluble rack or 15 holder for cards, advertisements, pictures, and like articles.

Another object of this invention is to provide a revoluble rack having a plurality of detachable card-holders which can be easily 20 and quickly detached at any desired time and readily placed in engagement with the rack when it is desired to display the cards contained by said rack.

My improved rack is particularly adapted 25 to be used in hotels, stationery-stores, and such places where a plurality of cards are to be displayed or conveniently reached.

Briefly described, my improved rack comprises a base having a standard upon which 30 is revolubly mounted a sleeve carrying two hexagon - shaped spider - frames, between which are supported card-holders adapted to contain a plurality of cards.

The detail construction of my invention 35 will be hereinafter more fully described and claimed, and, referring to the drawings accompanying this application, like numerals of reference designate corresponding parts throughout the several views, in which—

40 Figure 1 is a side elevation of my improved card-rack. Fig. 2 is an enlarged plan of the same. Fig. 3 is an enlarged detail sectional view of a portion of the rack, and Fig. 4 is a perspective view of one of the card-holders.

45 To put my invention into practice, I construct my improved card-rack of a suitable base 1, having a central upright or standard 2, the top of said standard being provided with a ball or pin-point bearing 3. Upon 50 the standard is detachably mounted a sleeve 4, the upper end of which is provided with a hexagon - shaped spider - frame 5, while mounted upon the lower end of the sleeve is a similar frame 6, said frame being retained 55 thereon by a link 7, carried by the lower end of the sleeve 4.

Each side of the hexagon frame 5 is provided with an upwardly-extending pin 8, and upon said pin is detachably mounted a card-holder 9. The card-holders 9 are adapted to 60 form the outer walls of the rack, and while I have herein described hexagon frames for supporting six card-holders I desire it to be understood that octagon frames or frames having a greater or lesser number of sides 65 may be readily used, the number of sides to said frames depending upon the size of the display-rack.

Each card - holder consists of two rods 10 10, the ends of which are connected together by plates 11 and 12. The plate 11 at the top of the card-holder is provided with a strap 14, by which the holder is secured to the pins 8 of the frame 5. The lower plate 12 is provided with a central 75 opening 15, by which the lower end of each card-rack is secured to the frame 6 by screws 16. Mounted between the rods 10 10 are a plurality of shelves or brackets 17, each bracket consisting of a plate 18, which is secured to the rods 10 10, each plate carrying a shelf-like extension 19, to which is secured an upwardly-extending wire frame 20, said frame being adapted to support a card upon the shelf-like extension 19. 80

When a plurality of cards are mounted in a card-holder, the cards supported by the shelves or brackets 17 are adapted to bear against one another, with the exception of the cards supported in the uppermost brackets or shelves. In this manner a great many 90 cards may be stored or supported upon my improved revoluble rack, and when it is desired to inspect the various cards supported by the rack said rack can be revolved to expose either side thereof. 95

The simplicity of construction used in connection with my improved rack permits of the same being mounted at a comparatively small cost, and it may be manufactured 100 from light and durable metal, whereby it may be supported upon a show-case or similar support.

Such changes in the construction and operation of my improved rack as are permissible by the appended claims may be resorted to without departing from the spirit and scope of the invention.

What I claim, and desire to secure by Letters Patent, is—

110 1. A display-rack embodying a base, a standard carried by said base, a sleeve rota-

tive upon said standard and with spider-frames at the upper and lower portions thereof, the upper of said spider-frames having upwardly-extending pins, a plurality of rack-frames each including vertical side members and transverse end members and with intermediate card-supporting racks, straps carried by said racks for bearing over said pins, and means for detachably connecting the lower ends of said racks to the lower spider-frames.

2. In a display-rack, a card-frame comprising spaced side rods and with end members consisting of sheet-metal plates bent at the ends around said rods, card-supporting devices comprising sheet-metal plates bent at the ends around said rods and each likewise extended laterally at its lower edge to form a card-supporting shelf and with the outer edge of the shelf turned upwardly and with its ends bent into sockets, a wire guard secured at the ends in said sockets, and means for suspending said racks from a supporting structure.

25 3. In a display-rack a supporting struc-

ture having at one end a plurality of upwardly-extending pins, a plurality of card-racks each constructed of spaced side rods and transverse end members formed of sheet-metal plates bent at the ends around said rods, 30 the upper of said plates having laterally-extending straps for bearing over said pins, means for detachably connecting the lower of said transverse pins to said structure, and a plurality of card-supports consisting of sheet-35 metal plates bent at the ends around said rods and extended laterally at their lower edges to form card-supporting shelves with the outer edges of the shelves extended upwardly and provided with sockets at the 40 ends, and wire frames supported at the ends within said sockets and extending substantially parallel with the said side rods and spaced therefrom.

In testimony whereof I affix my signature 45 in the presence of two witnesses.

MATHIAS ZEINER.
